UNITED STATES PATENT OFFICE.

THOMAS E. MURRAY, JR., OF BROOKLYN, NEW YORK.

ELONGATED CYLINDRICAL PROJECTILE-SHELL.

1,329,134.

Specification of Letters Patent. Patented Jan. 27, 1920.

Application filed October 25, 1918. Serial No. 259,619.

To all whom it may concern:

Be it known that I, THOMAS E. MURRAY, Jr., a citizen of the United States, residing at Brooklyn, in the county of Kings and State of New York, have invented a certain new and useful Improvement in Elongated Cylindrical Projectile-Shells, of which the following is a specification.

The invention relates to elongated cylindrical projectile shells of sheet metal of the type commonly known as trench mortar shells.

In the accompanying drawings—

Figure 1 is a longitudinal section of the shell. Fig. 2 is an elevation of the right hand end of the shell, as shown in Fig. 1.

Similar letters of reference indicate like parts.

The body portion A of the shell is cylindrical in shape and closed at one end by an integral wall B. In the opposite end wall C is a central opening surrounded by a flange D. The flanged opening is intended to receive the usual fuse and receptacle for the exploding charge, said fuse and receptacle not being here shown. The shell body A is here shown formed in two longitudinal interchangeable half sections E, F struck up from sheet metal, which sections after being placed with their straight edges in registering contact are united by electrically welding said edges together. G is the booster tube, here cup-shaped, for containing the propelling charge. The outer face of the end wall H of said booster tube is electrically welded to the outer face of the end wall B of the shell body. The circumferential wall of said tube may be perforated, as

shown at I, and said end wall H may be made, as shown, thicker than said circumferential wall. 40

By reason of this construction, I obtain an abutment formed by the welded walls at B and H, which is very strong and, therefore, offers ample resistance to the explosive force 45 of the propelling charge in the booster tube. I also avoid the use of any additional holding receptacle for the said charge inserted in the booster tube, thus saving the expense of manufacture of said part. The sections 50 of the shell body, including the integral end walls B, C, are made by a simple stamping operation, so that there is nothing to be added to complete the shell after the sections are welded together, other than the booster 55 tube described. Hence these projectiles can be made very rapidly and at greatly reduced cost as compared with other known constructions.

I claim:

An elongated cylindrical projectile shell closed at one end and formed of two longitudinally divided sections struck up from sheet metal and electrically welded together at their meeting edges, and a cup-shaped 65 booster tube concentric with said projectile shell and having the face of its end wall electrically welded to the face of the end wall of said shell.

In testimony whereof I have affixed my 70 signature in presence of two witnesses.

THOMAS E. MURRAY, Jr.
